W. MEYER

X-RAY APPARATUS

Filed March 9, 1922

UNITED STATES PATENT OFFICE.

WILLIAM MEYER, OF CHICAGO, ILLINOIS.

X-RAY APPARATUS.

Application filed March 9, 1922. Serial No. 542,210.

My invention relates to X-ray apparatus and more particularly to an improved table for use in taking X-ray photographs.

In taking X-ray photographs or shadowgraphs, as they are often termed, it is necessary to support the X-ray subject between the source of X-rays and the sensitized plate or film. In present day practice, surfaces for this purpose are made either of wood, celluloid or sheet metal such as aluminum. Surfaces of either of these materials present practical problems which my invention avoids. For example, wood not only has a grain which decreases the diagnostic value of the radiograph, but is hygroscopic and subject to shrinking and warping. Celluloid is deteriorated by X-rays and will not stand up for any length of time when subjected thereto. Sheet metal surfaces are chilling and disagreeable to the body of the patient, not of the highest permeability, and are yieldable and easily bent and distorted.

It is an object of my invention to provide an improved surface for supporting the X-ray subject between the source of X-rays and the sensitized plate or film, a non-hygroscopic surface having better permeability; a stiff surface having the necessary structural strength and no grain, one that will not shrink, warp, bend or be chilling or otherwise disagreeable to the body of the patient. The material I prefer to employ to this end is "bakelite", cotton fiber paper or a compacted isotropic web or felting of vegetable fiber cemented together by a substance such as "bakelite" or baking varnish, although any non-metallic, isotropic material which will not be deteriorated by X-rays may be employed within the scope of my invention.

Further objects of my invention are the provision of a novel, simple and effective means for positioning the tube standard along the table, novel, simple and effective means for visualizing the position of the plate or film from the side of the table and a novel, simple and effective method of and means for securing proper relative positioning of the X-ray tube and the plate or film.

In taking X-ray photographs this is important in securing clear, sharp detail uniformly over the photograph and the desired high diagnostic value.

Further objects and advantages of my invention will appear from the following detailed description, and the claims, taken with an inspection of the accompanying drawings, in which:

Figure 1 is a side elevational view of a table embodying my invention;

Fig. 2 is a plan view of the same;

Fig. 3 is a transverse vertical section taken substantially on the line 3—3 of Fig. 2;

Fig. 4 is an enlarged plan view of the plate or film holder; and

Fig. 5 is a side elevational view of the same.

The table shown in the drawings comprises the four corner posts 5 secured together by side pieces 6 and end pieces 7 to form a rectangular frame. A rail 8 extends between and is secured at its opposite ends to one pair of the posts or legs 5 adjacent their lower ends. The sides and ends of the table may be braced in any suitable or preferred manner and the legs or posts 5 may be provided with suitable casters or anti-friction rollers to facilitate movement of the table to any desired position. A top 10 having a centrally arranged longitudinally extending opening 11 extends, in the table shown in the drawings, partially over the table frame. The top 10 is supplemented by a top portion 12 to cover the entire table frame, it being understood that the top 10 may extend over the entire table or be divided or sectioned off as desired and that the width of the opening 11 which may be arranged through the top as desired will be varied to accommodate the particular plate or film holder to be used.

The plate or film holder 13 is formed to carry the plate or film which is preferably first arranged in a suitable cassette which is then mounted in the holder and held against displacement by a retention spring 14 secured to the bottom of the holder and having a bent or looped end projecting out from the end into which the cassette is inserted,

to engage the same upon insertion and prevent displacement thereof. A notch 15 in the base of the holder permits convenient access to the cassette as for the purpose 5 of removing the same from the holder. Strips 16 secured to the under surface of the top 10 along and projecting slightly beneath the opening 11 form tracks upon which the holder 13 is mounted for movement through the opening 11. An arm 18 secured to the under surface of the holder 13 is offset at 19 and extends out through a longitudinal slot or opening 20 in one of the side pieces 6 of the table into the path of 10 movement of the tube standard 25.

The standard 25 is supported and guided along one side of the table by guide rods 26 secured along the upper edge of the rail 8 and the lower edge of the adjacent side piece 20 6. Guide members 27 bearing rollers 28 cooperable with the rods 26 are clamped or otherwise secured in proper position upon the standard 25. These guide members are bored out to receive the tube standard 25 and the part which encircles the tube standard is split as shown at 24 to provide a 25 split clamp which may be readily applied to the tube 25 and securely fastened.

The adjustable tube stand may be clamped 30 in a fixed position anywhere along the table top by means of the clamping screw 23 which extends through the upper guide member 27 and engages the adjacent track 26. The guide rollers 28 which are grooved 35 to embrace the guide rods 26 permit of this clamping action. The radiographic or X-ray tube 30 is enclosed in a shield 31 supported with a suitable compression tube 32 by an arm 33 angularly adjustable about the end of an extension arm 34. The arm 34 is adjustably mounted at its opposite end in a frame or carriage member 35 which is in turn mounted upon the standard 25 for 40 vertical and angular adjustment thereupon. The tube may be of the Coolidge or any other suitable or preferred type. Where spring take-up reels are employed with a tube of the Coolidge type the leads extending 45 from the reels to the tube especially the lead in the cathode heating circuit are preferably insulated to prevent short circuiting and maintain a substantially constant resistance as the conductor is wound 50 upon the reel.

The top portion 10 of the table and thereby by the opening or plate tunnel 11 is covered by a covering or patient supporting surface 40 arranged over the top 10 and secured along the edge thereof by binding strips 41 of angular formation. These strips bind the covering 40 in place and present a neat and finished appearance.

The surface or covering 40 is preferably 65 made of "bakelite", cotton fiber paper, or a

compacted sheet of vegetable fiber cemented with "bakelite", baking varnish or the like, which I find has better permeability than the materials heretofore used, is stiff and will therefore not be quickly bent or distorted, has the requisite structural strength and no grain and hence will not cast confusing shadows upon the plate. It will not shrink, warp or be chilling or otherwise disagreeable to the body of the patient as is the case with metallic surfaces by reason of their high heat conductivity. The provision of a supporting surface for X-ray subjects having no grain decreasing the diagnostic value of the radiograph, one not deteriorated by X-rays, a relatively stiff non-hygroscopic surface having the requisite structural strength which will not warp or shrink or be readily bent or otherwise distorted or chilling or otherwise disagreeable to the body of the patient is novel so far as I am aware and is of great advantage to the art. I contemplate the use of any suitable or preferred compacted and cemented vegetable fiber or other non-metallic, isotropic material not deteriorated by X-rays in the formation of such a surface.

A pointer 50 carried by the tube standard 25 operates with a scale, which in the particular embodiment shown consists of markings 51 along the upper surface of the adjacent binding strip 41 to indicate the position of the standard and tube along the table and thereby facilitate positioning thereof. Adjacent its outer end the arm 18 carries a visualizing bar 52 movable with the holder 13 along the outer side of the table. This bar may be attached to the arm 18 through a downwardly extending mounting lug 53 or in any other desired manner. Its length and position longitudinally along the table is substantially that of the sensitized plate or film so that the position of the plate or film may be quickly visualized from the side of the table.

From the foregoing it will now be apparent that as the holder 13 is moved through the opening 11 into the desired position, the arm 18 will be moved therewith and the bar 52 positioned to indicate the position of the plate or film from the side of the table. The tube standard 25 and arm 18 are preferably so arranged that upon engagement therebetween the tube or source of X-rays 30 will be positioned substantially centrally over the plate or film in the holder 13 or at any rate the arrangement between the tube standard and arm 18 is 110 such that the desired relative positioning of the tube or source of X-rays and the plate or film will be had when the standard and the arm 18 are in engagement. Obviously, the tube standard may be moved into 120 125 130

the desired position as indicated by the pointer 50 and then upon moving the holder 13 to the position at which the standard is engaged by the arm 18 the desired positioning of the tube and standard will be had and at the same time the bar 52 will provide for visualizing the position of the plate or film from the side of the table. Of course, the holder may be moved to the desired position first and the standard then moved into engagement therewith with the same results. The upper surface of the table is provided with a pair of head pads 60 between which the head of the patient is adapted to be held.

10 I do not intend to limit the invention to the details of the particular embodiment which I have selected to describe, as I am aware and contemplate that modifications 20 and changes may be made without departing from the invention which is set out in the appended claims.

I claim:

1. In X-ray apparatus a subject supporting surface comprising a thin sheet formed 25 of a phenol product of condensation and interposed between the source of X-rays and the plate or film, said phenol product of condensation surface being presented directly to the source of X-rays and supporting the X-ray subject between the source of X-rays and said plate or film.

2. The combination with an X-ray table frame having a top with an exposure opening therethrough of means for supporting a plate or film on one side of said opening, a source of X-rays on the other side of the opening and a covering comprising a thin sheet of "bakelite" over said opening between the source of X-rays and the plate or film, said bakelite covering being presented directly to the source of X-rays.

3. In combination, an X-ray table, an upright tube standard mounted upon one side of said table for longitudinal movement therewith, a plate or film holder carried by the table and adapted for movement under the surface of the table and longitudinally thereof, and an arm attached to said holder and extending laterally from the side of the table on which the said tube standard is mounted to lie in the path of movement of the standard to position the holder with respect to the standard upon engagement between the standard and said arm.

4. In combination, an X-ray table, said table having a surface penetrable by X-rays, a plate or film holder movable beneath said surface, and means carried by said holder for visualizing the position of the plate or film carried thereby, said means comprising a member of substantially the length of the dimension of the holder in the direction of its movement, said member being positioned alongside the table with its length disposed

in the direction of movement of the holder and in substantial register with the dimension of the holder in that direction.

5. In combination, an X-ray table, said table having a surface penetrable by X-rays, 70 a plate or film holder adjustable beneath said surface, a tube standard movable along the table, an arm extending from the plate or film holder into the path of movement of the tube standard and means carried by 75 said arm for visualizing the position of the plate or film carried thereby, said means being of substantially the length of the holder in the direction of its movement.

6. In combination, a table frame, a top 80 having an opening therein, strips secured to the under surface of said top along said opening, a plate or film holder mounted upon said strip for movement through said opening, a tube standard movable along the 85 table, the plate or film holder having an arm projecting through a slot in the table frame into the path of movement of said standard, and means carried by said arm for visualizing the position of the plate or film carried 90 thereby.

7. The combination with an X-ray table having a plate tunnel of a plate or film holder movable in said tunnel, a separate tube standard movable along the side of the 95 table independently of the plate or film holder, the plate or film holder having an arm projecting from the side of the table into the path of movement of the standard 100 for centrally positioning the standard with respect to the holder.

8. The combination with an X-ray table having a plate tunnel of a plate or film holder movable in said tunnel, a separate tube standard movable along the side of the 105 table independently of the plate or film holder, the plate or film holder having an arm projecting from the side of the table into the path of movement of the standard 110 for centrally positioning the standard with respect to the holder, and means carried by said arm for visualizing the position of the plate or film holder.

9. The combination with an X-ray table 115 having a plate tunnel of a plate or film holder movable in said tunnel, a separate tube standard movable along the side of the table independently of the plate or film holder, the plate or film holder having an 120 arm projecting from the side of the table into the path of movement of the standard for positioning the standard and holder with respect to each other, and means carried by said arm for visualizing the position of the plate or film holder, said arm being of substantially the length of the dimension of the holder in its direction of movement and being positioned alongside the table with its length disposed in the direction of movement of the holder and in substantial reg- 125 130

ister with the dimension of the holder in that direction.

10. The combination with an X-ray table having a plate tunnel, a top and a side rail of a plate or film holder movable in the tunnel, a separate tube standard movable along the side of the table independently of the plate or film holder, said holder having an arm extending through a slot in the side rail and into the path of movement of the

standard for positioning the standard and holder with respect to each other, means carried by said arm for visualizing the position of the plate or film holder, a scale along the table top and a pointer on the standard 15 cooperable with said scale.

In witness whereof, I hereunto subscribe my name this 6th day of March, 1922.

WILLIAM MEYER.
